FREDERICK WILLIAM BAKER, OF OLDSWINFORD, STOURBRIDGE, ENGLAND, ASSIGNOR
TO TRINITY WHEEL CORPORATION, OF NEW YORK, N. Y., A CORPORATION OF NEW
YORK.

WHEEL DISK.

Application filed July 13, 1926, Serial No. 122,133, and in Great Britain June 8, 1926.

My invention relates to improvements in wheel disks such as are used in making vehicle wheels in which the disk serves as the connecting medium between the tire bearing 5 rim and the wheel hub. Such disks are made more or less resilient, and heretofore in attaining the desired resilience, it has been done by reducing the thickness of the disk at certain points, or by arcing the disk more 10 at or less, or otherwise, but such resilience has been uniformly distributed about the circumference of the wheel so as to make the disk equally resilient at all points. My invention is intended to produce a simple, 15 strong, and efficient disk for this purpose which has the resilience localized preferably symmetrically and at spaced intervals, to the end that at these points the disk will be more resilient than at other 20 places. This is done with the view of having the tire bearing rim attached in such a way that its supports will come opposite the more resilient or radially weakened parts 25 of the disk, and as the tire bearing rim yields more between its supports than elsewhere, the resilience of the wheel as a whole is equalized and distributed so as to get the required resilience without appreciable deformation.

30 The localizing of the resilience of the disk may be secured by a reduction in thickness of the disk at these points, by slotting the disk, or otherwise, the preferred method being by slotting the disk at these points as this is a simple means of attaining the desired result, and has the further advantage of ventilating the wheel in such a manner as to keep it cool. The slotting can be best effected by punching the disk at the necessary points, or at least making the slots in such a way that the edge portions will be turned in from the front face of the wheel, as this prevents any tearing or cutting edges, and furthermore the inturned

parts act to a certain extent like fan blades 45 so that when the wheel is turned they create a forced circulation of air.

Reference is to be had to the accompanying drawings forming a part of this specification, in which similar reference characters 50 indicate corresponding parts in all the views.

Figure 1 is a cross section of the disk embodying my invention taken on the line 1—1 of Figure 2 looking in the direction of the arrows. 55

Figure 2 is an elevation of the disk looking toward the inner face thereof.

Figure 3 is a broken diagrammatic detail showing the relation of the disk and the bearing member to the main wheel rim, and 60

Figure 4 is a detail showing another form of bearing member.

The disk is shaped with a central hub portion 10 which is shown flat and offset axially from the main part of the wheel, 65 having a central hole 11 for the axle, and the customary holes 12 to facilitate its attachment to the hub on the axle as usual. The middle portion 10 of the disk can, however, be given any preferred shape or configuration to facilitate its attachment to a hub. The surface 10 is inturned around its outer edge as shown at 13, this part merging into the outwardly flaring body portion 14 which is provided with essentially circular 70 or annular corrugations 15 located preferably near the outer or inturned rim portion 16. Obviously the corrugation 15 can be disposed at any desired point in the body 14 of the disk, but it is preferably near its outer perimeter and to get the best results the corrugation should be substantially concentric with respect to the rim portion 16. The edge of the rim portion 16 is preferably 75 flared outward as at 17, as this has a tendency to stiffen the disk at this point. 80

At different parts of the rim portion 16 and spaced preferably at regular intervals,

are bearing members 18 which form supports for the main wheel rim indicated at 18" in Figure 3. This bearing member can be conveniently pressed up from the metal 5 of the disk, but the invention is by no means confined to this or any particular means of forming the bearing members or of carrying said members. For example, in Figure 4 I have shown the rim portion 16 having bearing members 18' in the form of blocks which are secured to the rim, and I wish it distinctly understood that these bearing members can be arranged in any way between the rim portion 16 of the disk and the main felly 10 or rim 18" of the wheel, without departing from the invention.

One object of supporting the main felly or tire bearing rim 18" on this bearing members is to produce a certain resilience 15 in the felly, and in order that the resilience may be equal at all parts of the rim and opposite the bearing members 18 as well as between the members, the disk is weakened at points substantially opposite radially to the 20 bearing members 18. This local weakening of the disk can be accomplished in many ways, as by thinning the disk, or in any usual or preferred manner, to produce the increased resilience, but I prefer to slot the 25 disk at necessary points, and the slotting can be effectually made as shown at 20 in the corrugations 15. The slots are produced by forcing in the metal from the face side of the wheel as shown in Figure 1, so that 30 the edge portions of the slots 20 will be inturned. This prevents any raw edges on the face of the wheel which might cut or tear anything with which they come in contact, and further the inturned parts act to a cer- 35 tain extent like fan blades, and when the wheel is rotated, they make a forced circulation of air through the disk and around the wheel which has a tendency to keep the parts cool. These slots can obviously be produced in other parts of the disk structure to 40 make air circulation at desired points. In Figure 1 I have shown one of the members 18 perforated as at 19 to facilitate its attachment to an outer rim 18".

From the foregoing description it will be seen that I have thus produced a very simple, cheap, strong, easily made disk, which can be used to advantage in the manufacture of a disk wheel, and especially a wheel 45 50 55 of the type referred to.

It will be further noted that while the disk can carry a tire bearing member in any usual or preferred way, it lends itself especially to the type of wheel referred to in which bearing members 18 or the like are spaced on the disk rim or flange and that as the bearing members 18 are placed opposite the locally weakened parts of the disk and the portions of the tire bearing rim be-

tween said members opposite the non-weakened portions of the disk, the tire carrying rim as a whole will be supported equally resilient at all points.

1 claim:—

1. A wheel disk having radially weakened sectors and spaced peripheral rim bearing members disposed opposite the weakened sectors of the disk.

2. A wheel disk having radially weakened sectors and spaced rim bearing members disposed opposite the weakened sectors and projecting outward beyond the general periphery of the disk.

3. A wheel disk with a rim portion having bearing members thereon and with the disk body weakened radially opposite said bearing members to render it more resilient at said weakened parts.

4. A wheel disk with a rim portion adapted to lie within the main rim of a wheel and having resilient areas and bearing members on said rim portion spacing said rim portion from the main wheel rim.

5. A wheel disk having a rim portion and a corrugation in the body substantially concentric with the rim portion said corrugation being slotted at intervals.

6. A wheel disk having a rim portion having bearing members externally thereon, and a generally circular corrugation on the disk body, said corrugation being slotted at parts opposite the bearing members.

7. A wheel disk having a rim and spaced bearing members of substantially uniform width and length on the face of and integral with the rim to support a tire bearing rim.

8. A wheel disk having a rim and spaced bearing members extruded and projected from the outer face of rim for an equal distance both transversely and circumferentially of the rim.

9. A wheel disk formed from a single sheet with a peripheral rim and bearing members outwardly projecting for a short distance from the rim and of substantially uniform width and length.

10. A wheel disk having an axially offset hub portion, a body portion flaring axially outward from the hub portion, a rim at the outer edge of the body portion, and spaced bearing members on the rim.

11. A wheel disk having an axially offset hub portion, a body portion flaring axially outward from the hub portion and provided with a corrugation essentially concentric with the wheel rim, said corrugations being slotted at intervals, and a rim at the outer edge of the body portion.

12. A wheel disk having an axially offset hub portion, a body portion flaring axially outward from the hub portion and provided with a corrugation essentially concentric with the rim part of the disk, a rim portion

at the outer edge of the disk, and bearing members on the exterior of the rim for the purpose specified.

13. A wheel disk having slots opening through opposite sides thereof with the edges of said slots inturned.

14. A wheel disk formed of a single piece having a hub portion axially inturned and merging into an axially outwardly flaring

body, said body having weakened areas and merging into a rim at its periphery with spaced members on the rim to form supports for an outer tire bearing rim.

In testimony whereof, I have signed my name to this specification this 8th day of July, 1926.

FREDERICK WILLIAM BAKER.
